Attorneys

UNITED STATES PATENT OFFICE.

CORNELIUS SAMPIETRO, OF BROOKLYN, NEW YORK.

VIOLIN-BOW GAGE.

1,357,189.

Specification of Letters Patent.

Patented Oct. 26, 1920.

Application filed January 20, 1919. Serial No. 272,061.

To all whom it may concern:

Be it known that I, CORNELIUS SAMPIETRO, a subject of the King of Italy, residing at Brooklyn, in the county of Kings and State 5 of New York, have invented certain new and useful Improvements in Violin-Bow Gages; and I do declare the following to be a full, clear, and exact description of the invention, such as will enable others skilled in the art 10 to which it appertains to make and use the same.

This invention relates to gages, and it relates more particularly to an improved violin-bow gage.

15 One object of this invention is to provide a gage which is attachable to any bow of ordinary construction without changing the construction of any element of the bow.

Another object is to provide a device of 20 this character which, when attached, prevents the hairs of the bow from being tightened or stretched beyond a predetermined degree.

Another object of the invention is to provide 25 a device of this character which is adjustable to change the degree to which the bow's hairs can be stretched or tightened.

Another object is to provide a device of 30 this character which is durable and strong consistent with lightness and thorough efficiency.

Another object is to provide a device of 35 this character which consists of few and simple parts, and may be manufactured at a comparatively slight cost.

Other objects and advantages may become 40 apparent to persons who read the following details of description in connection with the accompanying drawings, in which:

Figure 1 is a side elevation of the handle element of a bow-staff and its adjuncts having my improved gage attached thereto.

Fig. 2 is an enlarged view, partly in section, of the structure shown in Fig. 1.

Fig. 3 is a view similar to Fig. 2, but showing the parts adjusted in the relaxed or loosened relation to one and other.

Fig. 4 is a transverse sectional view along the line 4-4 of Fig. 2.

Fig. 5 is a transverse sectional view along the line 5-5 of Fig. 2.

Fig. 6 is an elevation of a slightly modified form of the attaching element hereinafter described in connection with the remaining figures.

Fig. 7 is a sectional view illustrating another modified form.

Referring to these drawings in detail, in which similar reference characters correspond with similar parts throughout the several views, the numerals 7, 8, 9 and 10 refer, respectively, to the staff, frog, adjusting screw and hairs of a violin-bow of ordinary construction. To those who are familiar with the art, it is well known that the staff 65 7 is apertured to receive the shank and threaded portion of the screw 9, and that such threaded portion engages with a threaded element of the frog 8, so that by turning the screw 9, the frog 8 is moved 70 along the staff 7 toward the extreme end of the handle element of the staff, thereby stretching the hairs 10, and that by rotating the screw 9 in the opposite direction, the frog 8 is moved away from the extreme end 75 of the handle element. Moreover, it is usually known that a boss extends from the extreme end of the handle element, as indicated at 11, and that the head or handle element of the screw 9 is formed with an annular 80 recess 12 which fits over the boss 11. The present invention makes use of the boss 11 and recess 12 in a manner which will be described hereinafter.

The present invention consists broadly of 85 an attaching element 13, a gaging screw 14, a lock nut 15, and a spring 16, and I may add a washer 17. The attaching element 13, according to Figs. 1 to 5, inclusive, consists of the oblong member or bar 13 provided 90 with a screw-threaded aperture 18 and a non screw-threaded aperture or opening 19, this opening being enlarged at 20 to receive the boss 11, it being understood that the shank of the adjusting screw 9 extends 95 through this opening when the device is in its useful position. The margin of the opening 19-20 is serrated or formed with teeth 21 which are held in engagement with the extreme end of the handle element by means 100 of the compression spring 16.

The gaging screw 14 is provided with a head 22 at one end and with a knurled manipulative element 23 at its other end. The head 22 being disposed between the attaching element 13 and the adjacent end of the frog, prevents the screw from being removed from the aperture 18 while the device is attached to the violin-bow; and this arrangement also provides a wide area to en- 110

gage with the frog, so that danger of splitting or otherwise injuring the frog is avoided.

The lock nut 15 may be provided with 5 apertures 24 adapted for engagement with a wrench, key or spanner (not shown), so that a music teacher or other person may tighten the nut 15 to such extent that it can not be loosened by a person without the use 10 of a spanner or other nut-operating tool. By this arrangement, a music teacher can adjust the gage according to the amount of adjustment or tension he desires that the hairs 10 shall be given. When thus adjusted 15 a student or user of the bow may slacken the hairs 10 by turning the head of the screw 9 counter-clockwise until the parts have moved from the position shown in Fig. 2 to the position shown in Fig. 3. In this 20 latter position, it will be seen the spring 16 still retains some of its pressure upon the member 13, through the medium of the washer 17, so that the teeth 21 prevent accidental turning of the member 13 about the 25 shank of the screw 9, so that the gaging screw 14 retains its position in the path of movement of the frog 18 when the latter is subsequently moved to its hair tightening position. When the student or other person 30 adjusts the bow for use, the frog is stopped by its contact with the head 22, and the hairs 10 are thereby prevented from being overstretched or strained by an inexperienced or careless person.

35 In attaching the device illustrated in Figs. 1 to 5, inclusive, the screw 9 is removed from its engagement with the staff 7 and frog 8. The spring 16, washer 17 (when used), and attaching element 13 are successively strung 40 onto the shank of the adjusting screw, and the latter is then replaced in its useful position relative to the staff and frog, and this attaching operation may be completed within a fraction of a minute by any person of 45 ordinary ability.

In order that the attaching element may be even more quickly and easily attached, that is, without removing the screw 9 from its engagement with the elements 7 and 8, I may 50 employ the modified form shown in Fig. 6, in which the member 13' may be notched or slotted at 19', this member being identical with the member 13 in all other respects. In use this modified form of washer and 55 spring may be dispensed with or any appropriate form of spring may be employed in lieu of the spring 16. However, it is obvious that a spring of the character shown may be applied to the cavity 12 by loosening 60 the screw 9 sufficiently to allow its shank to be passed laterally between the helices of this spring; and by this mode of attaching the spring and attaching-member 13, the gaging attachment may be secured

to the bow without disconnecting the elements of the latter.

Where, in the foregoing, and in the claims, I have referred to an "opening" in the attaching member, this term "opening" is to be construed as meaning either an aperture, as shown in Figs. 2 and 3, or a notch which communicates with the center of the enlarged part 20 of the opening, as shown in Fig. 6, or in a similar construction which permits the elements 13 or 13' to be engaged 75 with the bow as illustrated in Figs. 2 and 3.

In the modified form shown in Fig. 7, the member 13' is different from the member 13, in that it is bent or offset at its middle part and extends toward the frog of the bow so 80 that the finger piece 23 does not interfere with the easy manipulation of the "nut" or finger piece at the end of the bow. By this arrangement the adjusting member 14 may be relatively short, being nearer the frog 85. Another feature of this modified form is the provision of a recess or spring seat 17'. 95

Although I have described this embodiment of my invention very specifically, it is not intended to limit this invention to these 90 exact details of construction and arrangement of parts, but I am entitled to make changes within the scope of the inventive idea disclosed in the foregoing description and the following claims.

What I claim as my invention is:

1. The combination with a violin bow comprising a bow-staff, a frog, a screw to move the frog along the bow-staff, and a nut to turn the screw, of a gaging attachment comprising an attaching element having one end portion seated between said nut and the adjacent end of the bow-staff, and formed with an opening through which said screw extends, the other end 105 portion of said attaching element being formed with a screw-threaded aperture, and a gaging screw threaded in said aperture and located in the path of movement of said frog so it will abut against the adjacent end of the frog to limit adjustment of the latter, said gaging screw being adjustable for varying its limiting effect upon 110 said frog.

2. A violin-bow gaging attachment comprising an attaching element formed with a screw-threaded aperture and having an opening therein to receive the portion of the adjusting screw of the violin-bow at the extreme end of the handle element of the 120 bow-staff, a gaging screw in said threaded aperture to abut against the frog of the violin-bow, the margin of said opening being formed with teeth to engage said extreme end, and elastic means to coact 125 with said adjusting screw for holding said teeth in engagement with said extreme end.

3. The combination with a violin bow

comprising a staff, a frog, and an adjusting screw operatively connected to the frog, the handle element of the staff having a boss extending therefrom, the adjusting screw 5 having a head with an annular recess therein; of an attaching member having a threaded aperture and an opening therein, said boss being fitted in said opening while said adjusting screw extends through this 10 opening so as to retain said attaching member in its normal position, elastic means in said annular recess to press said attaching member against the handle element of the staff, and a gaging screw in said threaded aperture and positioned in the path of adjusting movement of said frog. 15

4. The combination with a violin bow comprising a staff, a frog, and an adjusting screw operatively connected to the frog, the 20 handle element of the staff having a boss extending therefrom, the adjusting screw having a head with an annular recess there-

in; of an attaching member having a threaded aperture and an opening therein, said boss being fitted in said opening 25 while said adjusting screw extends through this opening so as to retain said attaching member in its normal position, elastic means in said annular recess to press said attaching member against the handle elements of the staff, and a gaging screw in said threaded aperture and positioned in the path of adjusting movement of said frog, the gaging screw having a headed end disposed between the frog and the attaching member to prevent removal of the screw and provide a wide frog-engaging area, said screw having a handle at its outer end and being provided with means for locking the gaging screw in its different adjustments. 35

In testimony whereof I have hereunto set my hand.

CORNELIUS SAMPIETRO.
